United States Patent Office

Des. 232,106

Patented July 16, 1974

232,106

TENNIS RACQUET

Joseph K. Dana, Wilbraham, and Peter R. Flak, Northampton, Mass., assignors to Questor Corporation, Toledo, Ohio

Filed Aug. 3, 1972, Ser. No. 277,812

Term of patent 14 years

Int. Cl. D21—01
U.S. Cl. D34—5 ST

Fig. 1.

Fig. 2.

Fig. 3.

Fig. 4.

FIG. 1 is a front view of a tennis racquet showing our new design.

FIG. 2 is a side view.

FIG. 3 is a top view.

FIG. 4 is a bottom view.

The dominant feature of our design resides in the appearance of the throat piece portion.

We claim:

The ornamental design for a tennis racquet, as shown and described.
